LIGHTING SYSTEM

**Kenneth L. Jones, Lansing, Mich., assignor to
General Motors Corporation, Detroit, Mich., a
corporation of Delaware**

Application July 12, 1943, Serial No. 494,311

6 Claims. (Cl. 315—83)

This invention relates to lighting systems for use on automotive vehicles, having the regular head, parking, tail and stop light indicating lamps of usual intensity and also with other head lights of special nature for black-out purposes.

This invention is particularly suitable for controlling the various lamp filaments for two conditions of driving, namely black-out driving with only the stop light burning normally when the brakes are applied, and night driving with the regular or service head and tail light burning.

An object of the present invention, is to provide a lighting system in which a plurality of different lamp circuits are connected in parallel with the source and each circuit is provided with a protective device which is arranged in a manner that when a particular one of the circuits is closed the protective device in said one circuit will cause the other protective device in the other circuit to open the said other circuit.

Further objects and advantages of the present invention will be apparent from the following description, reference being had to the accompanying drawing wherein a preferred embodiment of the present invention is clearly shown.

In the drawing:

Fig. 1 is a wiring diagram illustrating a preferred embodiment of the present invention.

Fig. 2 is a wiring diagram after the switch controlling the dim out lamps is closed.

Referring to the diagrams, a current source or storage battery 20, which is grounded at 21, is connected by a wire 22 with one end of a thermal or bimetal warp element 23. The thermal element is represented as being a bimetallic strip having one end fixed to a support 24 and having its free end normally engaging a stationary contact 25.

The thermal element 23 is so constructed that whenever abnormal current passes therethrough it will be heated causing it to warp or be deflected from the stationary contact 25 as shown in Fig. 2. The thermal element is preferably made from dissimilar metals or metal alloy which have enough high resistance in order to carry the normal current without generating enough heat to cause a deflection.

The contact 25 is connected by a wire 26 to a terminal 33 of a lighting switch 28. The switch 28 has a movable contact 29 adapted to move into one position to bridge stationary contacts 30, 31 and 32 and into another position to bridge contacts 32, 33 and 34. The contacts 31 and 33 are connected together by a conductor 35. The contact 30 is connected by a wire 36 with a park-

ing light circuit having a parking lamp 37. The contact 32 is connected by a wire 38 with a tail light circuit having a tail lamp 39. The contact 33 is connected by a wire 40 with one terminal of a stop light switch 41 actuated by the brake lever (not shown). The switch 41 is provided with a movable contact 42 movable into engagement with a contact 43 which is connected by a wire 44 with the stop light circuit having a lamp 45. The contact 34 is connected by a wire 46 with a terminal 47 of a dimmer switch having a movable contact 48 engageable either with contact 49 or 50. When the contact 48 is in the "dim" position the contact 48 will engage contact 49 to connect the "dim" filaments 51 of the main head lights 52 with the source of current. When the contact 48 is in "bright" position the contact 48 will engage contact 50 to connect the "bright" filaments 53 with the current source.

20 The wire 22 is connected also by a wire 55 with a terminal 56 of an auxiliary switch 57 having a movable contact 58 movable into engagement with a contact 59 and which is connected by a wire 60 with black-out lamps 61. The wire 60 is connected also by a wire 62 which is connected to one end of a heater element or a resistance unit 63. The other end of the heater is grounded. The heater element is adjacent the thermal or bimetal warp element 23. When the heater element is energized it radiates heat to warp the element 23 causing same to warp from the position of Fig. 1 to the position of Fig. 2.

The operation of the circuit is as follows: With the switch 57 closed current will flow from the current source 20 through the wire 55, switch 57, wire 60 from which the current is divided at point 70; a portion of the current will flow to the black-out lamp 61 to ground while another portion of the current will flow from the point 70 through wire 62, heater 63 and then to ground. The heater element upon being energized radiates heat to warp element 23 causing the free end thereof to leave contact 25 to break the connection between the battery and the contact 33. 45 Thus, it is obvious that in case the movable contact 29 is moved by an actuator 75 to bridge contacts 30, 31, 32 or contacts 32, 33, 34 no current can flow to the head lamps 52, the parking lamp 37 or to the tail lamps 39, due to the fact that the element 23 is out of engagement with contact 25 as clearly shown in Fig. 2. This condition of the element will be maintained so long as the switch 57 is closed and as soon as the switch 57 is opened the heater will be disconnected from the circuit thus allowing both the heater element

and the thermal element to cool and allow the thermal element to return to its normal position to again engage the stationary contact 25.

While the embodiment of the present invention as herein disclosed, constitutes a preferred form, it is to be understood that other forms might be adopted, all coming within the scope of the claims which follow.

What is claimed is as follows:

1. A lighting system for an automotive vehicle comprising, a current source; a main head light circuit; an auxiliary head lamp circuit; a thermal switch element in the main head light circuit and responsive to overload currents in the main lamp circuit and also to excessive heat to open the main head lamp circuit; a main switch in circuit with the source for controlling the head lamp circuit; an auxiliary switch in circuit with the source for controlling the auxiliary head lamp circuit; a resistance connected in a circuit in parallel with the auxiliary head lamp circuit which will heat up to activate the thermal element to open the main head lamp circuit upon closure of the auxiliary switch.

2. A lighting system for an automotive vehicle comprising, a current source; a main lamp circuit including head lamps, park lamps and a tail lamp; an auxiliary head lamp circuit; a switch for selectively connecting the park and tail lamp in circuit or the head lamps and the tail lamp in the circuit with the source; an auxiliary switch for connecting the auxiliary lamp in circuit with the source; a thermostat switch connected in series with the main lamp circuit and responsive to overload currents in the main lamp circuit and also to excessive heat to open said circuit; and a heater element adjacent the thermostat switch and arranged in a circuit upon closure of the auxiliary switch whereby the heater element is energized causing the thermostat switch to deflect and open the main lamp circuit.

3. A lighting system for a vehicle comprising, a current source; two sets of driving lamps, one of which is "dim-out" and the other is "bright"; two switches, one adapted to control the circuit between the "dim-out" lamps and the source, the other to control the circuit between the "bright" and the source; a thermal switch element connected in series in the "bright" circuit; an electrical heating element connected in parallel with the "dim-out" circuit, and said heating element being located adjacent said thermal whereby when the "dim-out" circuit is closed by its switch the heating element will radiate sufficient heat to warp the thermal element to break automatically the "bright" circuit.

4. An electrical signalling system for vehicles comprising; a main signal lamp; an auxiliary signal lamp; a current source applicable to all and capable of energizing any of the lamps; conductive circuits for causing current flow to either the main or auxiliary lamp from the source; switch means for closing each circuit; a thermal element switch in series with the circuit leading to the main signal lamp; and a resistance element arranged in proximity to the thermal element and connected in a circuit in parallel with the circuit leading to the auxiliary lamp only when the auxiliary lamp circuit is closed and heated to cause the thermal element to flex to interrupt current flow in itself and to the main signal lamp, said thermal element remaining in a flexed condition until the auxiliary lamp circuit is opened.

5. In an electrical control of the character described for controlling the operation of vehicle signal lamps; the combination comprising; a main lamp circuit; an auxiliary lamp circuit; independent switch means for opening and closing each of said circuits; manually-operable means for actuating said switch means to close said circuits, thermostat means in series with the main lamp circuit a resistance element connected in parallel with the auxiliary lamp circuit and in proximity to the thermostat means, whereby the thermostat means is rendered inoperative to complete the main signal lamp circuit when the auxiliary lamp circuit is closed, said thermostat means being effected by the heat of the resistance element to open the main lamp circuit, said thermostat means maintaining the main lamp circuit open only when the auxiliary lamp circuit is closed.

6. A control system comprising in combination; a current source; a stop light circuit; a main head light circuit; an auxiliary head lamp circuit; a thermal switch element in the stop light and main head light circuits and responsive to overload currents and also to excessive heat to open the stop light and main head light circuits; a first switch in circuit with the source for controlling the stop light circuit; a second switch in circuit with the source for controlling the main head lamp circuit; a third switch in circuit with the source for controlling the auxiliary head lamp circuit; a heat producing device connected in a circuit in parallel with the auxiliary head lamp circuit which will produce heat to flex the thermal element to open the stop light and the main lamp circuit upon closure of the third switch.
